CLAIM

The ornamental design for a vehicle cowl as shown and described.

DESCRIPTION

FIG. 1 is a front and left side perspective view of a vehicle cowl showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

A second embodiment of the claimed design for the vehicle cowl is a mirror image of the vehicle cowl as shown in FIGS. 1 to 7.
